UNITED STATES PATENT OFFICE.

WILLIAM J. SCHOENBERGER, OF CLEVELAND, OHIO.

VALVE.

Application filed August 23, 1924. Serial No. 733,842.

My invention relates to an improvement in valves, particularly in a needle valve for gas burners, heaters, etc., and my general object is to provide a valve in which the 5 needle member will be guided and held accurately in the center of the gas orifice and operate to discharge a straight stream of gas without objectionable obstruction, hindrance and malformation.

10 In the accompanying drawings,

Fig. 1 is a side view of my improved valve equipped with a detachable stem and handle.

15 Fig. 2 is an elevation of a modified form of the invention, and Fig. 3 is a sectional view thereof. Fig. 4 is a cross sectional view on line 8—8 of Fig. 3. Figs. 5, 6 and 20 7 are enlarged views of the gas nipple, guide ring, and the needle and outlet end of the gas valve, respectively.

In operating certain types of gas burners it is highly desirable and advantageous to jet a straight stream of gas into the burner at a high velocity under the control or setting of a needle valve.

25 An offset or eccentric position of the needle point in the round gas orifice is especially to be avoided, and the flow of gas to and through the orifice should not be impeded, nor eddy currents 30 created within the gas passages. Therefore, I have constructed a valve body 2 having an intake branch 3 communicating directly with a main gas discharge passage 4 through which a round needle valve stem 5 is adapted to extend and control the outflow of gas from a small round orifice 6 in the center of a hollow nipple 7. The round valve stem 5 is a fixed part of a larger screw-threaded member 8 having a knurled head 9 adapted to be engaged and rotated by hand, and the screw-threaded part 8 extends into one end of body 2 and engages internal screw-threads therein to effect longitudinal movement of the valve stem and a fixed setting of its pointed end relatively to orifice 6. However in tapping the body and forming the screw-threads it is difficult to center the tapered needle-point of the valve stem relatively to orifice 6 and maintain this central position during longitudinal 35 adjustments of the valve stem. When the needle point projects through the orifice and is not seated to close it entirely the needle point must be exactly central in respect to the round orifice if a concentric ring-shaped space for issuance of a straight

gas stream is to be obtained. To gain this desired positioning of parts for all adjustments of the needle valve and avoid eccentric settings and an irregular gas opening and a laterally deflected stream or malformation of the gas stream I provide means to positively center and guide the valve stem, and as shown this means comprises a thin perforated diaphragm or ring 23 within the outlet end of main passage 4, and the valve stem is free to rotate and slide within the central opening or perforation in this ring. The intake passage 3' 70 communicates with main passage 4 at one side of ring 23 and the gas has free and unobstructed flow around the valve stem and needle point from passage 3' to the gas orifice. Moreover, the inner end of screw nipple 7 is chamfered or beveled inwardly 75 at 12 to avoid banking the gas and creating an eddying current at the base of the nipple. The screw-threaded part 8 of the valve stem extends into the base end of the bore or 80 passage 4 in body 2 but the gas is prevented from leaking at the handle end of the valve stem by packing 15 and an adjustable gland member 16 screwed upon body 2.

The type of gas valve delineated embodies a plug valve 17 to control the flow of gas through intake passage 3', and the needle valve remains set after adjustment to any given condition. Plug valve 17 may be provided with a laterally-extending handle 18 as shown in Fig. 3, or a separate square rod or stem 19 of any desired length may be used to operate the plug valve as shown in Fig. 1. In the latter case a separate removable handle 20 may be affixed to the outer end of the square stem. A simple and efficient means of fastening the handle to the stem and the stem to the valve plug is illustrated in Fig. 1, and consists in providing each end of the stem with a beveled or inclined notch 21 to effect a tightening and locking action for a set screw 22.

105 The centering and guiding diaphragm or ring 23 for the valve stem is located at the discharge end of body 2 and is a separate piece in the form of a thin flat spider 23 having radial arms 24 adapted to be seated against a flat annular shoulder 25 at the base of the screw-threaded opening which receives screw-threaded nipple 7. This ring may be wedged or tightly fitted within the plug, or removably clamped in place by 110

nipple 7, and it serves to center and guide the needle end of the valve stem very closely in respect to the gas discharge orifice 6 in the nipple.

- 5 In placing spider-like ring 23 upon seat 25 the ring may be engaged slightly or loosely held by screwing the nipple 7 inwardly. Then the valve stem 5 may be rotated to seat its point within the orifice of 10 the nipple, thereby shifting the ring laterally on its seat providing it is not too tightly clamped by the nipple. The centering of the point thereby centers the guide ring, and then the nipple may be screwed 15 more tightly after the needle valve has

been retired, thus permanently centering the ring and needle point in respect to the gas orifice.

What I claim as my invention is:

A gas valve having a discharge passage, 20 a needle valve extending through said passage, a centering guide within said passage for said needle valve, and a discharge nipple having a port therein controlled by 25 said needle valve having an inwardly- chamfered end portion open to said passage.

In testimony whereof I affix my signature.

WILLIAM J. SCHOENBERGER.
